 Sigma Instruments, Incorporated, a corpora-
 tion of Massachusetts

Application September 16, 1948, Serial No. 49,483

5 Claims. (Cl. 175—339)

1

The present invention relates to electromagnetic structures and more particularly to structures of this character which are suitable for use as relays of the polarized type.

Among the objects of the invention is the provision of a compact and highly efficient polarity responsive electromagnetic structure.

An object of the invention is the provision of a three position electromagnetic structure having a neutral or normal position and which is capable of selectively assuming either of two operated positions in response to the polarity of an applied energizing current of appropriate magnitude.

A further object of the invention is the provision of an electromagnetic structure of the character described above which is highly resistant to shock and vibration thereby making it suitable for use in aircraft and other installations where adverse operating conditions of this type are likely to be encountered.

Another object of the invention is to provide an electromagnetic structure in which the movable element thereof is pivoted at a point in close proximity to its center of gravity thereby causing the movable element to be substantially unresponsive to the effects of linear accelerations imparted to the entire structure.

It is a feature of the invention that the magnets which are used to obtain the polarity selective response of the movable element have a conformation which enables them to occupy space in the structure which would ordinarily be unused. This feature has the advantageous effect of producing a more compact structure than would otherwise be possible.

A further object of the invention is to provide an electromagnetic relay which, when energized by a current of predetermined minimum strength, will move completely to its energized position and will build up appreciable contact pressure. Upon a decrease in current intensity below this predetermined strength, the full contact pressure will be retained, but as the net armature force approaches zero, the contacts will immediately open completely and without chattering. This type of operation is frequently referred to as "snap action." By avoiding contact chatter, rapid successive interruptions of the controlled electrical circuit are avoided and the life of the contacts is prolonged.

Other and further objects will become apparent upon reading the following specification together with the accompanying drawing forming a part hereof.

2

Referring to the drawing:

Fig. 1 is a plan view of a relay embodying the invention;

Fig. 2 is an elevational view, partly broken away;

Fig. 3 is a sectional view taken along the line 3—3 of Fig. 1, looking in the direction of the arrows;

Fig. 4 is a sectional view taken along the line 4—4 of Figs. 2 and 3, looking in the direction of the arrows;

Fig. 5 is a fragmentary sectional view showing the operation of the armature positioning mechanism;

Fig. 6 is a fragmentary sectional view showing a modified form of armature positioning mechanism;

Fig. 7 is an enlarged sectional view of a part of the armature positioning mechanism shown in Fig. 6; and

Figs. 8, 9 and 10 are graphical diagrams illustrating the forces acting on the armature for various angular positions thereof.

Referring to Fig. 3, a relay is shown having an energizing winding 11 provided with insulating spoolheads 12 mounted on a magnetizable core 13. A pair of magnetizable pole pieces 15 and 16 are shown secured to opposite ends of core 13 which are threaded to receive screws 17. Pole pieces 15 and 16 are secured firmly against shouldered portions 18 of core 13 at opposite ends thereof, the shoulder portions 18 being headed over at 19 providing efficient magnetic joints and a permanently assembled unitary structure. If desired, the shouldered portions 18 may be omitted, the core being positioned by the contact carriers.

An armature, designated generally as 20, is shown comprising two parallel and substantially coextensive elongated magnetizable members 21 and 22 joined together, the upper member 21 being curved upwardly a short distance at its central portion to provide a space for the accommodation of armature pivot pin 23 which extends transversely intermediate members 21 and 22, and is firmly gripped between these two members.

Extending longitudinally above and adjacent to winding 11 is a pair of permanent magnets 24 of substantially triangular cross section. Magnets 24 are magnetized with their ends of the same magnetic polarity, the opposite magnetic pole being situated at the central portion of each magnet. The two magnets are substantially identical both as to dimensions and magnetiza-

tion, two magnets being used to obtain a greater economy of space for a particular magnetic flux than may be obtained by the use of a single magnet. By the use of the triangular cross-section shown, the two magnets may occupy space in the structure which would otherwise be wasted, at least in part. The waste space is the result of the circular cross-section of winding 11 and the necessarily rectangular shape of the space available for the winding.

It will be seen that the structure thus far described will cause armature 20 to be attracted either to pole piece 15 or pole piece 16 depending upon which has the greater magnetic strength. This can be controlled at will by appropriate energization of winding 11. Upon energization with direct current of one polarity, one end of core 13 will assume the same polarity as the ends of the permanent magnets 24 and the magnetic flux through its associated pole piece will thereby be increased. The opposite end of the core 13 will have a magnetic polarity the same as that of the permanent magnet centers and the flux through the pole piece associated with this end of core 13 will be decreased. Accordingly, armature 20 will be attracted to the magnetically stronger pole. In the absence of a restoring spring, armature 20 will remain in this attracted position upon deenergization of winding 11.

Winding 11 may consist of two separate windings which may be connected in separate electrical circuits for differential operation, or it may be provided with a center tap, if desired, for operation of similar character. Where a precise magnetic balance is desired, the two separate windings may be derived by the use of paired wire. If a differential bridge circuit is to be used, quadded wire may be utilized to obtain four separate windings balanced both as to resistance and inductance and having substantially identical turn distribution. Such arrangements are commonly used in polarized relays for duplex telegraphic service.

The armature positioning mechanism comprises a pair of helical compression springs 24' disposed symmetrically with respect to armature pivot pin 23 on opposite sides thereof. At their upper ends, springs 24' engage lock nuts 25 carried by threaded studs 26. At their lower ends, springs 24' engage cup washers 27 through which studs 26 pass freely. The rounded lower convex surfaces of cup washers 27 engage beveled peripheral portions of apertures 28 in a stationary transverse plate 29.

Studs 26 are threadedly secured in armature members 21 and 22 and are provided at their lower extremities with lock nuts 30 which hold the studs 26 securely against rotation. Each stud 26 is provided with a collar-like portion 31 which is adjustable in height by rotation of the entire stud, lock nuts 30 having previously been loosened. If exactly symmetrical adjustment is desired studs 26 are carefully adjusted so that with armature 20 in its central position, the two collar-like portions 31 are just in engagement with the bottoms of the two cup washers 27, or they may engage the cup washers 27 with equal slight pressures. In the event, however, that the degree of engagement between collars 31 and washers 27 should be insufficient to pick up the full pressure of the compression springs 24' with the armature in its central angular position, then there will be a slight range of angular displacement in which the armature may move

freely without opposition from the springs. Ordinarily, the full pressure of either of the compression springs 24' will oppose any appreciable angular displacement of armature 20. With the armature in its normal, or neutral position the upward forces exerted by springs 24' on lock nuts 25, and hence on studs 26 are either substantially zero or substantially equal and therefore produce no effective torque. Any appreciable angular displacement of armature 20 will therefore pick up the full force of one or the other of the springs while the other will be rendered wholly ineffective being carried in its entirety by armature 20. This will leave the full compressive force of the other spring 24' completely unbalanced and hence acting with its full effect to oppose movement of the armature.

As an alternative adjustment, one of the studs may be adjusted to permit its spring to apply force to the armature throughout its entire range of angular travel. The other stud is then adjusted to permit its spring to engage the armature at approximately the midpoint of its travel with an initial force of about twice the initial pressure used in the symmetrical adjustment described above. It may also be desirable to use a spring in the latter position having a somewhat greater stiffness than the stiffness of the first spring. The resulting performance is substantially the same as for the symmetrical adjustment.

It will be thus seen that armature 20 will remain in its central angular position until an unbalanced force sufficient to overcome the effective resistance of either of the compression springs 24' is applied to one of the ends of the armature. The amount of such force required may be determined in part by the selection of appropriate dimensions for the compression springs and it may be adjusted to a certain extent by the positioning of lock nuts 25 at the upper ends of studs 26. This resistance of the compression springs is at least sufficient so that the magnetic attraction produced by permanent magnets 24 at either end of the armature will not overcome the initial spring loading in the event of a slight angular displacement of armature 20 from its central position. If armature 20 is to be self-restoring upon deenergization of winding 11, each spring 24' must exert a force sufficient to overcome the residual force of magnets 24 at the position of extreme displacement of armature 20 permitted in the particular case in question, and in the absence of magnetic influence from core 13. The magnitude of this initial spring loading will also serve to determine the amount of magnetic influence in core 13 required to cause appreciable displacement of armature 20 and hence determine the operating characteristics of the relay.

A modified form of positioning mechanism is shown in Figs. 6 and 7. A pair of hollow cylinders 35 are threaded both externally and internally. An adjusting screw 36 engages the internal threads of each cylinder 35 and the external threads engage armature 20. Within each threaded cylinder 35 is a helical compression spring 37 which at its upper end encircles a projecting central stud portion 38 of the adjusting screw 36. At its lower end each spring 37 engages a spherical ball 39, exerting a downward thrust upon the upper surface thereof. The extreme lower portion of each cylinder 35 is inwardly flared to retain ball 39. The lower surface of each ball 39 is positioned for engagement with

the upper surface of one of the pole pieces 15 or 16. If desired, the cylinders 35 may be rigidly mounted in any convenient position and the balls 39 may engage armature 20, the arrangement being symmetrical with respect to armature pivot 23.

Cylinders 35 are so positioned that with armature 20 in its central position the bottoms of the two balls 39 are just touching the pole pieces 15 and 16 and are equidistant therefrom or they may engage the pole pieces with equal slight pressures. As in the case of compression springs 24, the full initial load of either of the springs 37 is picked up when armature 20 has been angularly displaced by any very small amount. The dimensioning of springs 37 is also governed by the same factors as those which apply to springs 24.

The angle of travel of armature 20 is limited in a clockwise direction by an adjusting screw 40 and in a counter-clockwise direction by a similar adjusting screw 41. Screws 40 and 41 are symmetrically disposed with respect to armature pivot pin 23. The lower ends of screws 40 and 41 extend through armature 20 for engagements with the upper surfaces of pole pieces 15 and 16 respectively. Screws 40 and 41 are shown provided with lock nuts 42 to secure them in fixed positions of adjustment. Ordinarily, screws 40 and 41 will be of non-magnetic material in order to provide a magnetic gap when armature 20 is at either of its limits of angular displacement.

The amount of magnetic gap at the limits of armature travel will determine to a considerable extent the amount of residual force which will be exerted on the armature tending to retain the armature in its displaced position. This residual force is produced principally by the permanent magnets 24, although to some slight extent it may be increased by effects of remanence in the magnetic structure. By appropriate adjustment of screws 40 and 41 and compression springs 24', the armature may be made either self restoring or it may be caused to remain in its displaced condition by the action of residual magnetic forces. The effects of remanence in the magnetic structure are generally undesirable. These may be minimized by the use of suitable magnetic materials such, for example, as a ferro-nickel alloy, properly annealed.

The remainder of the structure which serves to form a complete relay comprises a plurality of fixed contacts 43 carried by brackets 44 which are shown provided with holes 45 for convenience in attaching wires. Brackets 44 are secured to blocks of insulating material 46 by rivets 47. Blocks 46 are in turn secured to pole pieces 15 and 16 by screws 17. The fixed contact position may be adjusted by loosening one of the screws 17, positioning the block 46 to provide the desired condition of adjustment and then tightening the screw 17 to maintain the adjustment. Pole pieces 15 and 16 are provided with flange portions 48 to which are secured a pair of non-magnetic side plates 49 covered by further side plates 50 of insulating material. Side plates 49 are shown with inwardly bent portions 51 having holes therein which provide mounting feet for the relay. Insulating side plate 50 carries a plurality of electrical terminals 52 which may be used for the connection of conductors extending to operating winding 11.

Disposed at opposite ends of armature 20 are a pair of insulating blocks 53 which carry flat flexible spring members 54 secured thereto by a plurality of rivets 55. The rivets 55 are shown

insulated at their lower ends from armature 20 by thin spacers 56 of insulating material interposed between the under surfaces of blocks 53 and armature 20. Blocks 53 and spacers 56 are shown held in engagement with armature 20 by the lock nuts 42 associated with adjustable armature stop screws 40 and 41. Additional fastening means may be provided if desired. Each of the spring members 54 lies directly above a further and more flexible member 54'. Member 54' is enlarged at its outer end to form a short transverse contact-carrying portion or head 56'. Secured to each portion 56' is a bridging contact plate 57. Spring member 54 extends freely through pierced slots in contact-carrying portion 56' under an offset part 57' of said portion. Owing to the flexibility of the narrow part of member 54' this construction provides very free angular articulation to compensate for the possibility of one fixed contact being higher than the other. The stiffer spring 54 provides the necessary resistance to insure good contact between the plate 57 and fixed contacts. Each of the transverse contact-carrying plates is arranged to establish contact between two adjacent stationary contacts 43 when urged into engagement therewith by angular displacement of armature 20. With the contacts in engagement, the action of restoring springs 24' will be aided by the force resulting from flexure of spring members 54 as indicated in Fig. 5. This flexure also causes a certain amount of sliding action or wiping between the fixed and stationary contacts thus tending to make the contact surfaces self cleaning.

Although the relay is shown with a contact arrangement which will close two electrically independent circuits in each of the two operated positions, other and different contact arrangements may be provided in a manner well known in the art. Where it is advantageous to establish connection directly to movable contact members, flexible conductors extending to such contact members may conveniently be terminated at electrical terminals carried by side plate 50 such as terminals 52.

The efficiency of the magnetic circuit comprising the permanent magnets 24 is increased by a transverse magnetic member 58 which extends between the central pole areas of the magnets 24 and is positioned in close proximity to the under side of the armature 20. A relatively stiff resilient curved spring member 59 is secured to the under side of transverse magnetic member 58 by a rivet 60 and tends to maintain magnets 24 securely in position.

Armature pivot pin 23 is journaled in side plates 49 at 61, being securely held between the armature members 21 and 22. This permits all bearing action to be confined to the ends of pivot pin 23 thereby increasing the life of the bearings and also tending to reduce friction. Side plates 49, which are non-magnetic, may be of brass and pivot pin 23 may be of steel thus providing suitable bearing materials for the minimization of wear.

The magnetic structure illustrated, as noted above, is capable of adjustment for "snap action" operation. The force curves which prevail in known polarized relay structures having centered armatures are illustrated in Fig. 8 in which the dashed line 81 illustrates the restoring force provided by the usual restoring spring and the curve 82 represents the operating torque produced by the magnetic structure. The abscissae represent angular displacement of the armature and the

ordinates represent torque acting on the armature. The vertical lines 83 and 84 represent the limits of angular displacement of the armature. Heavy curve 85 which represents the resultant of the magnetic forces and the forces exerted by a restoring spring of the designs used in relays of the character referred to, plus dashed parallel curves, indicates that with an increasing current a new equilibrium is established at point "0," and the armature will change its position as the current increases in a manner similar to the needle of a milliammeter. As a result, contact closure will take place with zero contact pressure and no appreciable contact pressure can be obtained until the energizing current has increased substantially above the minimum current required to effect contact closure. As a result, there is a range of current values in which the contact pressure will be unsatisfactory and in which contact chattering will occur, especially under conditions of 20 mechanical vibration of the entire magnetic structure.

Referring to Fig. 9, it will be seen that the armature positioning mechanism of the present invention changes the operating characteristics considerably from those of the conventional relay. The dot-dash line 91 represents the torque of the restoring springs. Curve 92 represents the magnetic torque as in the case of Fig. 8. The heavy line 93 represents the resultant of the 25 spring forces and the magnetic forces. The arrangement of the springs 24' of the relay is such that no angular displacement of the armature 20 can occur until a torque sufficient to overcome the initial loading of the springs 24' has been applied to the armature. This minimum torque is indicated at points 95 and 95'. The curves also indicate that the rate of increase of the 30 magnetic torque is greater than the rate of increase of the opposing spring torque. As a result, once the magnetic torque is sufficient to overcome the initial loading torque produced by the springs, the armature will move immediately to its limit of travel. To release the armature of the relay, the operating current is reduced to a 35 point where the magnetic torque can just be overcome by the spring torque. Once this condition has been attained and the armature starts to return to its normal position, as the magnetic torque 40 is reduced more rapidly than the spring torque, the armature will move immediately to its normal or neutral position. There will not be any 45 stable condition of zero contact pressure since the armature will be ready to return completely to its normal position as soon as the magnetic torque is reduced to a value just slightly less than spring torque.

This effect is illustrated in Fig. 10, in which the spring torque has been drawn reversed in order to facilitate a comparison of the characteristics with those of the magnetic torque. The dot-dash line 101 represents the spring torque, drawn reversed. Curve 102 represents the magnetic torque with no 50 magnetic influence from operating winding 11. Curve 103 represents a displacement of curve 102 by a current flow in operating winding 11 sufficient to cause operation of the relay armature in a clockwise direction. At the limit of armature travel represented by vertical line 104, it will be 55 seen that the magnetic torque of curve 103 exceeds the spring torque represented by dotted line 101 by a substantial amount. This excess is available for the production of contact pressure without further increase in the operating current. Upon a decrease in operating current sufficient to 60

bring the magnetic torque characteristic to the position indicated by curve 105, the magnetic torque will be just slightly less than the spring torque. The spring torque will immediately take control and restore the armature to its normal or neutral position. It will be noted, that as the armature proceeds toward its normal position, the spring torque represented by line 101 exceeds the magnetic torque of curve 105 by a continually increasing amount. This causes the release of the relay armature to take place in a positive manner and avoids the presence of an undesirable stable condition of substantially zero contact pressure.

I have shown what I believe to be the best embodiments of my invention. I do not wish, however, to be confined to the embodiments shown but what I desire to cover by Letters Patent is set forth in the appended claims.

I claim:

1. In a device of the class described, a magnetizable core, a pair of pole pieces operatively associated with the ends of the core, an operating winding on the core disposed intermediate the pole pieces, a centrally pivoted armature having its ends in responsive proximity to the pole pieces, and an elongated magnetized member extending parallel to and in operative proximity to the armature having a magnetic pole area substantially midway of its length arranged to influence the armature near the center thereof and two pole areas at its ends of polarity opposite to that of the intermediate pole area arranged to influence the pole pieces with like polarity and to substantially equal degree, whereby the position of the armature may be selectively controlled by appropriate energization of the operating winding, said operating winding being of substantially circular cross section, a framework for supporting the operating winding, core, pole pieces, armature and elongated magnetized member, said framework providing a space of substantially rectangular cross section for accommodation of the operating winding and magnetized member, said magnetized member being of substantially triangular cross section and means for supporting the same in a corner of the rectangular space in which the operating winding is mounted with the vertex of the triangle in proximity to such corner, and with the long side of the triangle in proximity to the circumference of the operating winding.

2. A device as in claim 1 in which the magnetized member is a permanent magnet.

3. A device as claimed in claim 1 in which two magnetized members are provided supported in adjacent corners of said rectangular space adjacent to the side of the space nearest to the armature, said magnetized members being permanent magnets, and a bridge of magnetizable material connecting said magnets near the centers thereof.

4. In an electromagnetic relay selectively responsive to the magnitude and polarity of an energizing current applied to an operating winding thereof, a non-magnetic frame, a pair of magnetizable pole pieces mounted in said frame, a magnetizable core with an operating winding thereon and having its opposite ends secured to the pole pieces, an elongated magnetized member mounted in said frame and extending between said pole pieces substantially parallel to the operating winding and in proximity thereto, and having a central magnetic area of one polarity and end magnetic areas of opposite polarity, a magnetizable armature pivotally supported near its center of gravity on said frame, the arma-

ture, when in neutral position, extending symmetrically into magnetically responsive proximity to the pole pieces, and preloaded spring means associated with the armature for resisting movement thereof towards either pole piece until a predetermined flux has been built up, said spring means comprising spring holding sleeves adjustably mounted on the armature at opposite sides of the pivotal support thereof, springs mounted in said sleeves, adjustable abutment means carried by said sleeves for preloading said springs, movable abutments mounted in said sleeves and engaging said springs, said sleeves and abutments being provided with coacting formations permitting movement of said abutments relatively to said sleeves in a direction to increase the load on said springs but limiting movement of said movable abutments in the opposite direction, and fixed abutment surfaces carried by the frame with which the movable abutments are normally in engagement when the armature is in neutral position, movement of the armature out of neutral position under the influence of the energizing current causing the spring carrying sleeve at one side of the armature pivot to move towards the corresponding fixed abutment surface, thereby increasing the load on the spring carried in said sleeve, the spring carrying sleeve at the other side of the armature pivot simultaneously moving away from the corresponding abutment surface and carrying the movable abutment member therein out of engagement with said surface.

5. In an electromagnetic relay selectively responsive to the magnitude and polarity of an energizing current applied to an operating winding thereof, a magnetizable core with an operating winding thereon, magnetizable pole pieces fixed to the ends of said core, a pair of non-magnetic frame members fixed to said pole pieces on opposite sides of said core, an elongated permanent magnet mounted between said frame members and extending between said pole pieces substantially parallel with the operating winding and in proximity thereto, and having a central magnetic area of one polarity and end magnetic areas of opposite polarity, a magnetizable armature pivotally supported near its center of gravity between said frame member, the armature, when in neutral position, extending symmetrically into magnetically responsive proximity to the pole pieces, and preloaded spring means for resisting movement of the armature towards either pole piece until a predetermined flux has been built up, said spring means comprising a pair of

adjustable spring devices, one for resisting movement of said armature in one direction, and the other for resisting movement of the armature in the other direction, each of said devices including a spring, adjustable holding means for the spring by which the spring may be restrained in adjustable preloaded condition, a movable spring pressed engagement member, stop means on the spring holding member limiting movement of said engagement member in one direction, said engagement member being movable away from said stop means in a direction to increase the stress on the spring, and abutments for engagement with the engagement members of said spring devices, said spring devices and abutments constituting pairs of reacting elements mounted for relative movement, one pair of said elements being mounted on the movable armature and the other pair of said elements being mounted on a stationary support, whereby upon movement of the armature in either direction one of said engagement members will be moved away from its corresponding abutment while the other element will be moved so as to increase the tension of its spring, said engagement members being normally balanced in engagement with their corresponding abutments when the armature is in neutral position.
